UNITED STATES PATENT OFFICE.

SAMUEL W. HUDSON, OF HUDSONDALE, PENNSYLVANIA.

STEAM-MOTOR.

SPECIFICATION forming part of Letters Patent No. 258,580, dated May 30, 1882.

Application filed December 15, 1881. (No model.)

To all whom it may concern:

Be it known that I, SAMUEL W. HUDSON, of Hudsondale, in the county of Carbon and State of Pennsylvania, have invented certain new and useful Improvements in Steam-Motors, of which the following is a specification.

My invention is designed more especially for compressing air for ventilating purposes. It is shown in the accompanying drawings as arranged to create a blast within a closed chamber or compartment with which the ventilating-shaft of a mine or other place to be ventilated communicates. The pipe through which the blast is blown out of the closed chamber projects into a larger pipe which extends from the exterior of the compartment inwardly. The action of the blast is to entrain or draw into the inwardly-projecting pipe air from the closed compartment, thus creating a vacuum therein; and the air from the mine constantly rising to correct this partial vacuum insures a draft through the mine and thorough ventilation. I make no claim, however, herein to the arrangement of the ventilating-shaft, closed chamber, and blast thus generally described, as it forms the subject-matter of another application filed simultaneously herewith.

My present invention constitutes an improvement upon the steam-motor for which Letters Patent of the United States, No. 249,527, were granted to me November 15, 1881; and its object is to utilize as nearly as possible all the steam supplied by the boiler. To this end my invention, broadly stated, consists in the combination of two or more motors of the general construction shown in my said patent, the steam from the boiler being admitted directly into the first motor only, the other machine or machines being driven by the steam which is carried up between the piston-heads of the first motor, and which would otherwise be lost or condensed.

In the accompanying drawings, Figure 1 is a perspective view, partly in section, with the inclosing chamber broken away, illustrating my organization of apparatus. Fig. 2 is a plan view of the same; and Fig. 3 is a diagrammatic sectional elevation for illustration merely, the motors being arranged, for conven-

ience of illustration, with the axes of the sprocket-pulleys parallel, but not coincident.

Four steam-motors, V, W, X, and Y, are arranged side by side, as described. These motors are each shown as consisting of two upright tubes, the lower portions of which are of larger diameter than the upper part. In each motor an endless chain carrying piston-heads which comparatively snugly fit the smaller portions of the tubes passes through them and over sprocket-pulleys S S'. The lower pulley, S, is mounted in suitable bearings within a sealed or closed tank filled with fluid—say water—with which the tubes of the motor are connected, the tubes of each motor being open at the top, as shown. The air-compressing tube V' is connected by a tube, A, from any suitable point of its smallest diameter with the enlarged portion of the air-compressing tube W'. A similar tube, B, connects the smaller portion of the air-compressing tube W' with the enlarged portion of the air-compressing tube X' of the next motor, while the smaller portion of the tube X' is in turn connected with the enlarged portion of the tube Y' of the next motor by a tube, C. The steam tubes or cylinders V², W², X², and Y² of the several motors are tubularly connected as follows: The smaller portion of the cylinder V² is connected by a tube, M, directly with the larger part of the cylinder W². From some point of the cylinder V² above the connection of the tube M a tube, N, is connected with the smaller portion of the steam-cylinder W², from which a tube, O, extends to the larger portion of the steam-cylinder X². From some point of the steam-cylinder W² above its connection with the pipes N and O a tube, P, extends to the smaller portion of the steam-cylinder X², from which a tube, Q, extends to the larger portion of the cylinder Y². The purpose of this organization, as will hereinafter be fully set forth, is that the steam which passes up the cylinder V² of the motor V will, by means of the pipes M, N, O, P, and Q, be carried to and serve to operate the motors W, X, and Y, while the air which is carried down the compressing-tubes W', X', and Y' will be transferred through the pipes A, B, and C to the compressing-pipe V' of the first motor, and the sum of the work of the

several motors be accumulated in the compressing-pipe V' to produce the requisite blast.

From a point in each of the steam-cylinders above the pipe-connections described I provide exhaust-openings D , which communicate with a common exhaust-pipe, E , which delivers the steam thus collected into the steam-cylinder Z^2 of the motor Z . The lower sprocket, S , of this motor is mounted in suitable bearings within its tank, while its upper sprocket, S' , is secured to the shaft on which the upper sprockets of the other machines are secured. The motor Z is provided with an endless chain and piston-heads, and a tube, Z' . The upper ends of the tubes, however, are not open to the atmosphere, but are connected by a dome, Z^3 , which includes the sprocket S' . This dome should be suitably packed where the shaft S^2 passes through it. The tank in which the tubes of the motor Z are partly submerged should be left open.

I introduce at the top of the tube Z' , at z , a condensing jet or spray. Just below the smaller portion of this tube is a pipe, Z^4 , into which any remaining steam enters. A condensing jet or spray is introduced at the top of this pipe from the pipe Z^5 .

The operation of the apparatus thus far described is as follows: The steam from any suitable generator is introduced at the opening V^3 into the cylinder V^2 , and operates, as will be understood, to drive up the piston-heads therein and rotate the sprockets. The piston-heads entering the tube V' carry air down it. A considerable portion of the steam ascending the cylinder V^2 is delivered by the pipe M to the cylinder W^2 and causes the piston-heads to be driven up therein, the effect of which is to draw air down the tube W' , which air is delivered through the pipe A into the compressing-tube V' of the first motor. It should be noted at this point that the diameters of the tubes of the motor W are greater than those of V , and that the tubes of each of the succeeding motors increase in diameter. The effect of this is that a greater volume of air will be carried down the compressing-tube of each succeeding motor, and this volume being delivered into the smaller preceding tube creates a greater pressure therein than would otherwise be the case. I prefer to thus construct the motors, though they may be made of the same size.

Returning now to the operation of the steam, a portion of the steam not carried from the cylinder V^2 by the pipe M is carried by the pipe N to the cylinder W^2 , and is there mingled with the steam rising in that cylinder, and is carried by the pipe O to the cylinder X^2 , causing it to operate, as will be understood, and deliver the compressed air through the pipe B to the tube W' . The steam from the cylinders W^2 and X^2 is similarly carried to the cylinder Y^2 , and that motor is caused to rotate, as described, delivering the compressed air through the pipe C to the tube X' .

It will be obvious that the compressed air of all the motors will be accumulated in the pipe V' , and will be delivered from thence through the blast-pipe. This operation can be performed, as will readily be seen, because of the fact that no amount of pressure between any two piston-heads within the smaller portions of any of the tubes of the motors will affect the operation of the machines, because it will be obvious that the pressure will be equal in both directions against both piston-heads, and will therefore be neutral. The combined exhaust-steam from the four motors is carried by the tube E to the steam-cylinder Z^2 , driving the piston-heads up it. The steam will be carried around down the tube Z' and will be partially condensed by the spray or jet at z , and will be finally delivered into the condensing-pipe Z^4 and condensed. 85

It will thus be seen that practically all the steam introduced into the first motor will be utilized, the amount which escapes from the upper open ends of the several cylinders being very trifling. The power of the machine Z is applied to the shaft S^2 , as is the power of all the other machines, and thus the combined action of them all produces a requisite uniform motion of all the parts.

Suitable stop-cocks, R , are placed on each tank V , W , X and Y to draw off water to regulate the amount within the tank, while of course any desired quantity of water may be introduced by means of a hose through the top of the pipes. Of course the length of the enlarged portions of the pipes V' , W' , X' , and Y' must be sufficient to prevent the water which will be driven up into them by the pressure of the steam from covering the air-outlet. It is not necessary to make the piston-heads fit the several tubes or cylinders very tightly, as the water which is carried up by the pistons forms a sufficient packing. To make this effective, however, it is desirable to somewhat elongate the pistons; but in compressing air the lengthening of the pistons occupies the space within the tubes and reduces the working capacity of the machine. To remedy this I form the piston-heads cup-shaped, as shown in the motor V . By this means I attain the requisite length to insure a proper packing, and at the same time lose comparatively little space. Where the apparatus is, however, used solely as a motor, it is desirable that the piston-heads should be of considerable length, and that the spaces between them should be comparatively small. Piston-heads H of this kind are shown in the motor Z . These piston-heads may be cast hollow and turned or ground down, and are preferably connected by links I to form the chain. This is of importance, because the pressure of the steam is just as effective within the small space between the piston-heads as they are forced up by the steam in the tube as it would be in the larger spaces. Less steam, however, is carried up between the piston-heads, and

such a construction is therefore advantageous and desirable.

The apparatus herein described is shown as organized for a particular purpose; but I do not limit myself to such an arrangement. For instance, a series of motors having steam-cylinders only might be connected by the steam-tubes, as herein described, and the combined power of several machines applied for any other purpose to the common shaft S^2 , and, as above remarked, I may use two or more machines, as may be desired, and motors similar to V , W , X , and Y may be used alone or in connection with the motor Z .

The blast generated by the apparatus above described may be used for any purpose to which a blast of that character may be applied. For instance, where the apparatus is used, as shown, for ventilating a mine, the blast may be used, or such portion of it as is necessary, for the smelting-furnaces, provided that the character of the blast obtained is such as not to impair the quality of the ore being treated. In almost every instance, however, the blast would be applicable to furnaces for steam-boilers for heating or for applying power in connection with the working of the mine. In order to thoroughly lubricate the working parts of the machinery, I place in the tube of each motor a sufficient quantity of oil. The oil of course remains upon the surface of the water in the tubes, and as the chain and pistons revolve they pass through it, and the parts are thus thoroughly lubricated, and as practically all portions of the machinery in contact with the water are kept thoroughly oiled the parts will not rust and become stiff, but are kept clean and operative.

I have described my improved apparatus as a steam-motor, but it is of course equally operative as a compressed-air motor, and I contemplate so using it. In that event, however, condensation in the final machine would be impossible, and the use of the condensing-jet and condensers therefore unnecessary, so that when the machine is thus used the pipe Z^4 should be left open to the atmosphere.

When the machine is designed for compressed air only I would prefer to dispense with the smaller portion of the tube Z' and the dome Z^3 .

and have the tank sealed, as is the case with 50 the other motors.

I am aware that heretofore in engines of this character it has been proposed to use machinery-oil as a seal and fluid abutment of the engine, and I do not therefore make any claim to such 55 subject-matter, but limit this branch of my invention as specifically set forth in my claims.

Having thus described my invention, what I claim as new, and desire to secure by Letters Patent, is—

1. The combination of two or more distinct and independent motors, substantially such as described, connected by steam-pipes and so arranged that the waste steam from the first motor serves to operate the other motor or motors, as set forth. 65

2. The combination of the motors V W X Y , their connecting steam-pipes, the motor Z , and the steam-pipe E , substantially as set forth.

3. The combination of the several independent motors, their sprockets S' , the connecting steam-pipes, and the common shaft S^2 , substantially as set forth. 70

4. The combination of the motors V W X Y , having steam-cylinders and air-compressing 75 tubes, their connecting steam-pipes, and their connecting air-pipes, substantially as set forth.

5. The combination of the steam-cylinder, the air-compressing tube, the endless chain, piston-heads and sprockets, a fluid seal, and a 80 closed or sealed tank, substantially as set forth.

6. The combination of the steam-cylinder, the air-compressing tube, the endless chain, the cup-shaped piston-heads, sprocket-pulleys, and a fluid seal, substantially as set forth. 85

7. The combination of the steam-cylinder, the sprocket-pulleys, the elongated piston-heads, having comparatively small spaces between them, the endless chain or connecting-links, and a fluid seal, substantially as set 90 forth.

In testimony whereof I have hereunto subscribed my name this 25th day of November, A. D. 1881.

SAMUEL W. HUDSON.
